UNITED STATES PATENT OFFICE.

EARL W. LESHER, OF CLEVELAND, OHIO.

SHINGLE.

1,425,992.

Specification of Letters Patent. Patented Aug. 15, 1922.

Application filed April 4, 1921. Serial No. 458,244.

To all whom it may concern:

Be it known that I, EARL W. LESHER, a citizen of the United States, residing at Cleveland, in the county of Cuyahoga and 5 State of Ohio, have invented certain new and useful Improvements in and Relating to Shingles, of which the following is a specification.

This invention relates to a roof, more particularly to the shingles therefor.

One object of the invention is to provide a plurality of shingles for roofing purposes having along adjoining edges interlocking devices, whereby they may be rapidly laid 15 in spaced and aligned relationship.

Another object of the invention is to provide a shingle which is so cut along its opposite sides that it may be spaced from and align with another shingle or shingles of 20 like construction to form a durable roof covering.

A further object of the invention is to provide a shingle having along its opposite side edges complementary walls permitting 25 the shingles to be cut from a strip of material without waste and correlated economically in spaced and aligned arrangement.

Another object of the invention is to provide shingles for covering purposes each 30 having along their opposite sides elements shaped for correlation with the elements on adjacent shingles to permit alignment one with another and with the shingles comprising an adjacent row of shingles.

35 A further object of the invention is to simplify the construction of shingle disclosed in my co-pending application Serial No. 428,546.

40 Other objects of the invention will be apparent to those skilled in the art to which my invention relates from the accompanying drawings taken in connection with the following description.

45 In the drawings, Figure 1 is a perspective view of a shingle embodying my invention and made according to my improved process.

Fig. 2 is a plan view of a plurality of shingles showing them arranged side by side 50 and in spaced and aligned relationship.

Fig. 3 shows a plurality of rows of shingles illustrating the manner in which they are assembled and laid on a roof.

55 Fig. 4 is a top plan view of a roll of material, such as asphalt or other composition

of matter, partly broken away, showing a portion extended and a set of shingles embodying the form of construction shown in Figs. 1, 2 and 3, cut therefrom.

Fig. 5 is a plan view of a plurality of assembled shingles embodying a slightly modified form of my invention.

Fig. 6 is a plan view of a plurality of shingles embodying the invention shown in Fig. 5, illustrating the manner in which they are cut.

In the drawings, 1 indicates as an entirety a shingle embodying or constructed according to my invention. To illustrate the application of my invention, I have shown in 70 the drawings a plurality of shingles arranged side by side and overlapping the shingles in an adjacent lower row, in the usual way, (see Fig. 3) to form a roof or roof covering. Each shingle may be stamped 75 out of suitable material, such as asphalt or composition, by a suitable die, but in carrying out my improved process, for economical reasons, I prefer to use knives or cutters, suitably mounted on a roller or rollers, 80 and to cut the shingles from an endless strip or roll A of asphalt, as will be understood from Fig. 4. When made in this last referred to manner, I am enabled to avoid all waste of material (except small portions α 85 of the strip along the outer edges of the outer shingles of each set and sections α' —only one section being shown—at the opposite ends of the strip) and at the same time to so cut the strip of material that the interlocking or interengaging devices on one edge of each shingle may be correlated with the interlocking or interengaging devices on the opposite edge of the adjacent shingle to insure (1) proper spacing and alignment of 90 the shingles in each row relative to each other and (2) overlapping of each row of shingles on the adjacent lower row of shingles to effect uniform exposed surfaces of the rows in the completed roof covering. 100

To prepare the strip A for use in carrying out my process, I first cut the free edge of the strip A along a broken line B to form three offsets b each spaced from the adjacent side edge of the strip or the adjacent offset of the next shingle a distance equal to the width of a shingle, allowance being made for the projecting members along the outer edge of one end shingle. In my process I prefer to first cut the strip 110

A on longitudinal broken lines C, the outer ends of which coincides with the side wall of each offset b , and which extend inwardly equal distances from the inner ends of the offsets. In carrying out this step of my process I prefer to provide knives or cutters to make the cuts C' and C* which serve to provide the extensions and complementary recesses, to be later referred to, on the outer side edges of the end shingles of each set. In providing these cutters, I utilize the longitudinal edges of the strip A to form portions of the side edges of the outermost shingles, thereby using the full width of the strip and avoiding unnecessary waste of material. I then cut the strip on the transverse broken lines D, D, to complete the cutting out of the set of shingles, and sever them from the body of the strip A. As shown, this latter cut serves to form the ends of the next set of shingles. It will be understood, however, that these steps or operations may be reversed or effected simultaneously. As shown, I am enabled to provide four shingles from a single width of material. These operations are continued until the strip A is entirely cut into shingles.

Each longitudinal cut is formed with a plurality of offsets 2, 3, to form on one side edge of one shingle a pair of extensions 4, 5, (the latter being twice the length of the former) and on the adjacent side edge of the adjoining shingle complementary recesses 6, 7. The extensions 4, 5, are preferably connected or merged together, as shown in the drawings to facilitate the cutting thereof. As shown, the offset 3 is spaced from the transverse cut D and the offset 2 is spaced from the offset 3 a distance equal to the length of the offset b , respectively, so that each of the extensions 4, 5, and each of the complementary recesses 6, 7, is of the same width and of a width equal to that of the offsets b . In laying the shingles 1 side by side in rows, the extensions 5 of one shingle fits into the recess 6 of the adjoining shingle with its lower end wall 3^a formed by the offset 3 in interengagement with the end wall 2^a of the recess formed by the offset 2. As the extension 5 and recess 6 are of a width equal to the length of the offset b , it will be seen that the engagement of the extension 5 with the end wall of the recess 6 will serve to arrange the shingles in the row with their lower or exposed end edges in alignment; and furthermore, since the extension 5 has a length that of the extension 4, the shingles will be spaced from each other a distance equal to the length of the extension 4, as will be fully understood from Figs. 2 and 3. Accordingly, it will be seen that the extensions 4 and 5 and recess 6 will serve as self spacing devices for the shingles. Those portions of

the cuts C between the offsets 2, 3, are parallel to the remaining portion of the cut C; accordingly, when the shingles 1 are assembled side by side, as shown, they will be parallel to each other. The lower end wall 4^a of the extension 4 serves as a guide to indicate to the workman how much one row of shingles should overlap the next adjacent lower row to provide the proper or desired exposed surface in each row. As shown in Fig. 3, the lower ends of the shingles in one row are aligned with the end walls 4^a of the shingles 1 of the next lower row so that the workman may leave the desired amount of exposed surface on the latter row. It will thus be seen that the end walls serve to insure parallelism of the lower edges of the rows of shingles, and uniformity in the width of exposed surfaces in the rows, and that they also serve to co-operate with the interlocking or interengaging devices 5, 6, to provide aligned relationship of all the shingles.

As shown in the drawings, the transverse cut D comprises a plurality of transverse sections, one for each shingle, connected by longitudinal sections, which serve to form the offsets b for the next adjacent set of shingles to be cut from the strip A. As each transverse section of the cut D extends past the upper end of the adjacent longitudinal cut C, it will be seen that it serves to provide the upper end wall of the extension 5 on each shingle; further, since the longitudinal sections of the cut D are equal to the length of the offsets between the shingles of a set, it will also be seen that each extension 5 is spaced from the upper end wall of the adjacent shingle a distance equal to the length of the offsets.

In Figs. 1 to 4 inclusive, the offsets 2, 3, are arranged at right angles to the longitudinal sections of the cuts C. If desired, the offsets for forming the extensions 4, 5, and complementary recesses 6, 7, may be inclined relative to the longitudinal sections of the cut C, as shown at 8 in Figs. 5 and 6.

To those skilled in the art of making articles of the class described, many alterations in construction and widely differing embodiments and applications of my invention will suggest themselves, without departing from the spirit and scope thereof. My disclosures and the description herein are purely illustrative and are not intended to be in any sense limiting.

What I claim is:

1. A shingle having along one edge projections extending one beyond the other but of equal width longitudinally of the shingle and along its opposite edge a recess complementary in shape and size to the shorter projection but in transverse alignment to said longer projection.

2. A shingle having along its opposite

- edges sets of extensions of equal width but of different lengths and complementary recesses, said recesses being out of transverse alignment with said extensions, respectively, 5 so that when the shingle is correlated with another similarly formed shingle one of the extensions on one shingle will interengage a recess on the other shingle to align and space them.
- 10 3. A shingle having along one side edge a pair of extensions of different lengths but of equal width arranged end to end, and formed in its other side edge with recesses complementary to said extensions but out 15 of transverse alignment therewith, the uppermost extension being spaced from the upper end of the shingle a distance equal to the width of each extension, whereby the extension of greater length will interengage with the wall of of a recess of another shingle to space and align them. 20
4. A shingle having along one side edge a pair of extensions of different lengths but of equal width arranged end to end, and formed in its other side edge with recesses 25 complementary to said extensions but out of transverse alignment therewith, the uppermost extension being spaced from the upper end of the shingle a distance equal to the width of each extension, whereby the 30 extension of greater length will interengage with the wall of a recess of another shingle to space and align them, the lowermost extension serving as a guide in laying the shingles of a superposed row of shingles. 35

In testimony whereof I affix my signature.

EARL W. LESHER.
